UNITED STATES PATENT OFFICE.

ALDEN B. STARR, OF NEW YORK, N. Y.

MACHINE FOR MANUFACTURING PAPER CARTONS.

1,161,545.

Specification of Letters Patent.

Patented Nov. 23, 1915.

Application filed April 4, 1914. Serial No. 829,701.

To all whom it may concern:

Be it known that I, ALDEN B. STARR, a citizen of the United States, residing at the city of New York, borough of Manhattan, 5 and State of New York, have invented certain new and useful Improvements in Machines for Manufacturing Paper Cartons, of which the following is a full, clear, and exact description.

10 This invention relates to a machine or press adapted for use in the manufacture of packages or receptacles.

The machine has special application in the manufacture of paper cartons whose 15 walls are provided with an internal bead near one end which forms a seat for the disk shaped bottom of the carton, the walls of the carton extending beyond the bottom being crimped or curved down over the bottom to securely hold it in place. It has been found that from cutting a tube of a proper size for a carton from a length of tubing and also from subsequent grooving of the tube, that variations frequently occur in the heights of the cartons. If the paper cartons are to be filled by the use of 20 automatic machinery, this variation in the heights of the packages interferes, to a material extent, with the proper feeding of them to the automatic machine and with the 25 following operations during which they are filled. Any variations in the heights of the cartons will also hinder them from being properly packed for transportation.

30 The primary object of the invention is, therefore, to provide a machine or press which is adapted to reduce the cartons to a uniform height and with this object in view, the invention consists essentially in 35 two synchronously revolving plates, which plates are arranged slightly out of parallelism with the distance between the plates at their points of greatest separation sufficient to permit the packages or cartons to be inserted in upright position therebetween, whereby, upon the rotation of the plates to a position in which the distance between the plates is decreased, a pressure will be exerted upon the walls of the package in a 40 direction parallel to its longitudinal axis. Since the walls of the package are weakest in the zone of the internal bead, the pressure exerted will cause this bead to flatten, tending to force the walls of the bead together and reduce the carton to a standard 45

height. The flattening of the internal bead will also tend to make the joint between the cylindrical walls more secure so that the package is equally as well adapted to be used as a container for liquids as solids.

50 Other objects of the invention will be apparent to one skilled in the art from the description and will be particularly pointed out in the appended claims.

In the accompanying drawing, the figure 65 represents a front elevation of a machine constructed in accordance with and embodying the principles of my invention, portions of the same being shown in section.

The bed of the machine consists of a cylindrical pillar or post 2 mounted on a base 3. Projecting upwardly from the center of the top of the post and arranged axially therewith is a spindle 4, which is of sufficient diameter to withstand the bending strains to which it is subjected, as will later appear. The lower portion of the spindle is vertically disposed and carries a circular dial-plate 5 of relatively large diameter which forms the revolving table upon which 70 the cartons are placed. The plate 5 is preferably ribbed as at 6 and is provided with a hub 7 to give it the requisite strength to avoid any tilting of the plate on the spindle 4.

75 Concentrically disposed on the circular plate 5 is an annular ring 8 of somewhat less diameter which forms a stop or gage against which the walls of the cartons 9 abut when placed upon the table, so that the 80 cartons are arranged radially equi-distant from the center of the table. In the accompanying drawing only two of such cartons are shown, but it is to be understood that the 85 cartons are successively fed or placed upright upon the dial-plate 5 in the annular space between the ring 8 and the peripheral edge of the table, with their walls almost touching each other. The table or dial-plate 90 5 is revolved by means of a worm-wheel 10 mounted on the spindle 4 below the plate, which worm-wheel is secured to the dial-plate in any approved fashion. Projecting laterally from the post 2 is a substantially 95 right-angled bracket 11 which is cut away 100 at its upper end to provide bearings 12 for the worm 13 which is mounted on a shaft 14. Tight and loose pulleys 15 and 16, respectively, are mounted upon the free end of the 105 shaft 14.

The upper portion of the spindle 4 is bent at a slight angle to the vertically-disposed portion, the bend occurring substantially at the zone designated 17. Mounted on the bent portion of the spindle 4 and interposed between two split collars 18 and 19 which are adjustably clamped to the spindle 4, is a second revoluble plate 20 which is also preferably ribbed and which is free to revolve upon the spindle. The plate 20 is connected for rotation to the lower plate 5 by means of vertically disposed pins 21 which are rigidly fastened to the lower plate and pass through elongated slots 22 in the upper plate, the slots being longer than the diameter of the pins so that the upper plate will be free to move angularly with respect to the pins when rotated. Since the upper portion of the spindle 4 is arranged at a slight angle to the vertically-disposed lower portion, the upper revoluble plate 20 is slightly out of parallelism with the lower plate 5, and upon the rotation of the plates the distance between the opposite portions of the working faces of the two plates will vary in different angular positions of the plates, the portions being displaced the maximum distance apart when they are in a position shown on the right hand side of the view and a minimum when they occupy a position at 180° therefrom, or, in the position shown at the left hand side of the view.

The operation of the machine will now be described.

Assuming that the plate or table 5 is being driven continuously by the worm-drive shown and the plate 20 rotated therewith by means of the pins 21. The cartons 9 are successively placed in upright position upon the table with their walls abutting the ring 8 when opposite portions of the working faces of the plates 5 and 20 successively reach their point of greatest separation or in the position shown at the right hand side of the figure. As the plates are rotated the portion of the working face of the plate 20 opposite the upper end face of each carton will gradually approach the end surface of the cylindrical walls of the carton until it rests thereon and finally exerts a pressure which will be transmitted to the walls of the carton to crush the internal annular bead of the package and slightly flatten the same as is clearly shown in the left-hand side of the figure. The joint between the disk forming the bottom of the carton and the walls is therefore made more secure so that the cartons are adapted for use as containers for liquids. The collars 18 and 19 are clamped upon the upper portion of the spindle 4 in such position that the plate 20 is maintained separated from the plate 5 a distance which, when the opposed portion of the working faces of the plates 5 and 20, which cover the end faces of the carton, are a minimum dis-

tance apart the distance is equal to the correct height of the package and since each of the cartons 9 is arranged upon the table 5 with its walls abutting the ring 8 which is concentrically arranged with the table 5, it is evident that the cartons will all be reduced to a uniform height. During the other half of the revolution the portions of the faces of the plates 20, which are covered by the end faces of the carton, will, successively, gradually move away from the table 5 until the position shown in the right-hand end of the figure is again reached by the portions of the working face of the plate 20 opposite the end face of each carton, where the same may be removed and replaced by a new one.

Since the diameters of the revoluble plates 5 and 20 are relatively large and the amount which the plates are arranged out of parallelism with each other relatively small, the fact, that the upper plate 20 will crush the cylindrical walls of the carton so that its end face is out of parallelism with the other end face, is immaterial for by choosing plates of sufficiently large diameter this distortion may be rendered negligible.

I claim:—

1. In a machine of the character described, two revoluble presser plates having plane working surfaces mounted in spaced relation to each other with their working faces slightly out of parallelism with each other and adapted to receive a paper carton in upright position between them, and means for synchronously revolving said plates.

2. In a machine of the character described, two revoluble presser plates having plane working surfaces mounted in spaced relation to each other with their working faces slightly out of parallelism with each other and adapted to receive a paper carton in upright position between them, and means for synchronously revolving said plates, one of said plates being adjustably mounted whereby the distance between the working faces of the plates may be varied.

3. In a machine of the character described, two revoluble presser plates having plane working surfaces arranged in spaced relation to each other and adapted to receive a paper carton in upright position between them, and means for synchronously moving said plates in rotary paths in which the distance between opposed portions of the working faces of the plates varies slightly in the different angular positions of the plates.

4. In a machine of the character described, two revoluble presser plates having plane working surfaces arranged in spaced relation to each other and adapted to receive a paper carton in upright position between them, means for synchronously moving said plates in rotary paths in which the distance between opposed portions of the working faces of the plates varies slightly in the different

- angular positions of the plates, and means for bodily adjusting one of said plates relatively to the other.
5. In a machine of the character described, two revolute presser plates having plane working surfaces spaced from each other, the working surfaces of said plates being arranged slightly out of parallelism with each other and adapted to receive a carton between them in the position of greatest separation of the opposed portions of the working faces of the plates and upon rotation of the plates to exert a pressure upon the walls of the carton when the opposed portions of the working faces of the plates gradually approach each other, and means for synchronously revolving said plates.
- 10
6. In a machine of the character described, two revolute presser plates having plane working surfaces mounted in spaced relation to each other with their working faces slightly out of parallelism and adapted to receive a paper carton between them in upright position, means for synchronously revolving said plates, and means mounted on one of said plates for spacing the cartons at an equal distance from the center of said plate.
